BEDSPRING SUPPORT

Application filed April 2, 1928. Serial No. 266,571.

This invention relates to bed spring supports, particularly to a support for carrying the bed springs in wooden bedsteads.

As is well known the usual wooden bedstead has upright wooden side bars extending along the sides of the bed and connecting the head and foot portions of the bedstead, and it is common practice to support the spring by fastening wooden strips along the lower part of the inside wall of these upright bars by means of screws or other means, and then placing slats crossways of the bedstead resting at their opposite ends on these strips. The bed spring frame rests directly on these slats. However, these are unsatisfactory and a great deal of trouble is experienced by the slats breaking or dropping off the strips, and the strips themselves break off or become loosened from the side bars. To overcome these objections we have devised metal brackets or supports which positively engage over the upper edges of the side bars of the wooden bed, and are so supported at their lower ends that there is no danger of their yielding or giving away.

Referring to the accompanying drawings in which we have shown one embodiment of our invention,

Fig. 1 is a vertical section through the side bar member of a wooden bedstead showing our improved spring support applied thereto and in side elevation.

Fig. 2 is a detail elevation of the upper edge of this side bar looking from the right of Fig. 1.

Fig. 3 is a detail section of the upper edge of this side bar.

Fig. 4 is a side elevation of our improved support detached from the side bar member of the bed, and

Fig. 5 is an elevation thereof looking from the right of Fig. 4.

In the construction illustrated the upright side bar member of a wooden bedstead is shown at 10. Our improved support comprises a strap or supporting member 11 which may be a piece of flat metal having a hook 12 at its upper end adapted to engage over the upper edge of the wooden side bar 10, as shown in Fig. 1. It is preferred

that a notch 13 be cut in the upper edge of the bar 10 to receive this hook so that the parts will be flush with the top and outer surfaces of the side bar to give a neat and attractive appearance, and the outer end of the hook may be covered by a molding 14. The distance between the side bars of different beds varies and also the distance between the side bars of the bed spring frames also varies. To accommodate for these variations the lower portion of the supporting member or strap 11 is extended downwardly and inwardly, as shown at 15, from the inner surface of the bar 10 and then extends inwardly and upwardly to form a rest 16 for the side bar 17 of the spring frame, and it is preferred that the inner end 18 of the support be curved upwardly, as shown, to retain this bar in the support. This rest is preferably made somewhat wider than the diameter of the bar 17 so as to compensate for the differences in the spacing between the side bars of the bed spring frames, and therefore, the same support may be employed for different spring frames. This is indicated by the dotted lines of Fig. 1 which indicate how the bars of different spacing would be received in the support.

As this rest is spaced inwardly somewhat from the inner wall of the side bar 10 it is desirable that some supporting means be provided so that it is not necessary that the strain be taken by the supporting member 11, as it would tend to yield outwardly. For this purpose we connect to the rest 16, or some other suitable portion of the support 11, a stud or brace 19 which extends horizontally toward the side bar 10 and carries an adjustable abutment 20 adapted to engage the side bar 10 and rigidly support the member 11 in proper position. This abutment may be mounted in various ways but we prefer to thread the inner end of the brace 19, as shown at 21, and have the abutment 20 tapped to engage this threaded end, and the abutment may be in the form of a nut so that it may be readily turned by means of a wrench to secure the proper adjustment and retain the lower portion of the support 11 in proper position.

It will be apparent from the foregoing description that the device is extremely simple in construction and will form a rigid and reliable support for the bed spring frame. The upper hook portion 12 forms a positive support for the bracket on the side bar of the bedstead which is in no way liable to give way, and the greater the weight the more firmly it is held in position. The brace 10 19 at the lower part thereof retains the rest for the side bars 17 in proper position and prevents the support 11 from bending outwardly under the weight placed on the support, while the adjustable abutment 20 may 15 be easily adjusted to retain the rest in the proper position. In applying the support to the bedstead it is merely placed in position with the upper hook portion 12 engaging the upper edge of the side bar, and the abutment 20 engages the inner wall of the side bar. It is, 20 therefore, unnecessary to perform any machining operations or set any screws, and no tools are required.

Having thus set forth the nature of our 25 invention, what we claim is:

A bed spring support comprising a strap having a hook at its upper end to engage over the upper edge of the side bar member of a wooden bed and having its lower 30 end extending inwardly and upwardly to provide a recess to receive the side bar of a bed spring frame, a brace connected to the lower portion of said strap and extending toward the side bar member, and an adjustable nut on said brace to engage the 35 side of said member.

In testimony whereof we affix our signatures.

ISADORE B. ROSENBERG.
ROBERT MULWITZ.
